UNITED STATES PATENT OFFICE.

DAVID McDougall, of Fall River, Massachusetts.

CLOTHES-LINE PROP.

No. 880,748.

Specification of Letters Patent.

Patented March 3, 1908.

Application filed March 4, 1907, Serial No. 360,420. Renewed January 9, 1908. Serial No. 410,011.

To all whom it may concern:

Be it known that I, DAVID McDougall, a citizen of the United States, residing at Fall River, in the county of Bristol and State of Massachusetts, have invented a new and useful Clothes-Line Prop, of which the following is a specification.

This invention relates to clothes line props and has for its object the provision of a knock down prop including a plurality of pivoted sections one of which is movable laterally to closed position so that said sections may be compactly folded for transportation or shipment.

15 A further object of the invention is to provide means for locking the folding section in extended position, and means for retaining the locking means in inoperative position when the pivoted sections are folded.

20 With these and other objects in view the invention consists in the construction and novel combination and arrangement of parts hereinafter fully described, and illustrated in the accompanying drawings, it being understood that various changes in form, proportions and minor details of construction may be resorted to within the scope of the appended claims.

25 In the accompanying drawings forming a part of this specification: Figure 1 is a perspective view of a knock down prop constructed in accordance with my invention. Fig. 2 is a similar view showing the prop in folded or collapsed position. Fig. 3 is a 30 transverse sectional view of the same.

35 Similar numerals of reference indicate corresponding parts in all of the figures of the drawings.

The improved prop forming the subject 40 matter of the present invention consists of relatively stationary and movable sections 5 and 6 having their adjacent ends over-lapped and pivotally united by a transverse bolt or pin 7.

45 The free end of the relatively stationary section 5 is provided with a pointed terminal 8 adapted to enter the ground while the free end of the upper or movable section 6 is bifurcated to form a slot 9 adapted to receive 50 an ordinary clothes line. The bifurcated end of the upper section 6 is preferably reinforced and strengthened by a transverse rod or pin 10 having oppositely disposed heads 11 which bear against the adjacent longitudinal

edges of the sections 6 and thus serve to assist in preventing said section from splitting or cracking. As a means for locking the sections 5 and 6 in extended position there is provided a pair of clamping collars or sleeves 12 and 13 each preferably formed of a single 55 piece of flat metal having its opposite ends over-lapped and riveted together at 14.

The collar 12 is slidably mounted for longitudinal movement on the section 6 while the collar 13 is mounted for sliding movement 65 on the section 5, said collars being movable to operative position in engagement with the pivoted ends of the adjacent sections so as to lock said sections in alinement with each other when the prop is used in the ordinary 70 manner. As a means for retaining the locking collars 12 and 13 in inoperative position during the folding operation suitable keepers 15 are secured to the longitudinal edges of the sections 5 and 6, said keepers being each 75 preferably formed of a single piece of metal having its opposite ends rigidly secured to the pivoted sections and its intermediate portion bent downwardly to form a central depending projection or lug 16 defining spaced 80 slots or recesses 17 and 18 adapted to receive the clamping collars. When it is desired to

use the prop the upper or movable section 6 is swung laterally and upwardly on its pivotal axis 7 until the opposite longitudinal 85 edges of the pivoted sections are in alinement with each other after which the locking collars 12 and 13 are moved into engagement with the ends of adjacent sections thus securely locking the sections against lateral 90 movement. In order to fold the sections the collars 12 and 13 are released from the pivoted ends of said sections and forced laterally against the inclined faces of the spring 95 pressed lugs or projections 16 thus elevating said lugs and permitting the collars to engage the slots or recesses 18 and in which position they will be held against accidental displacement during the folding operation. After the collars 12 and 13 have been released from 100 the pivoted ends of the sections 5 and 6 the section 6 is forced laterally and downwardly to the position shown in Fig. 2 of the drawings and in which position the prop may be 105 conveniently carried from place to place. Attention is called to the fact that when the prop sections are folded the clamping collars 12 and 13 will be disposed one above the

other and thus permit said sections to lie substantially parallel with each other throughout their entire lengths.

Having thus described the invention what is claimed is:

- 10 1. A clothes line prop including pivotally united sections foldable one upon the other and movable laterally to extended position, a locking member slidably mounted on each section and adapted to engage the end of the adjacent section, and means carried by each section and forming a guide for the adjacent locking member for holding said members in operative and inoperative position.
- 15 2. A clothes line prop including mating sections having their lower ends over-lapped and pivotally united, said sections being foldable one upon the other and movable laterally to extended position, keepers secured to one longitudinal edge of each section, and locking collars slidably mounted in the keepers and adapted to engage the end of the adjacent section for locking said sections in extended position.
- 20 25 3. A clothes line prop including pivotally united sections foldable one upon the other and movable laterally to extended position,

straps secured to one longitudinal edge of each section and provided with a central depression defining spaced slots, and a locking member slidably mounted in said slots and adapted to engage the end of the adjacent section for locking said sections in extended position.

4. A clothes line prop including pivotally united sections foldable one upon the other and movable laterally to extended position, straps secured to one longitudinal edge of each section and having an intermediate portion thereof bent downwardly to form a spring pressed projection, and collars slidably mounted on the sections at said straps and movable into engagement with the end of the adjacent section for locking said sections in extended position, said collars being held in inoperative position by engagement with the spring pressed projections.

In testimony that I claim the foregoing as my own, I have hereto affixed my signature in the presence of two witnesses.

DAVID McDougall.
